United States Patent Office

Des. 196,069
Patented Aug. 20, 1963

196,069

SLIDE RULER

Alex Augustin, Sparrowbush, N.Y.
(Gardner St., Port Jervis, N.Y.)

Filed Jan. 24, 1963, Ser. No. 73,304

Term of patent 7 years

(Cl. D52—6)

FIG. 1.

FIG. 2.

FIG. 3.

FIG. 4.

FIG. 1 is a plan view of the ruler according to the present invention;

FIG. 2 is a side elevational view, both sides being similar;

FIG. 3 is a bottom view of the ruler; and

FIG. 4 is an end view of the ruler according to the present invention.

I claim:

The ornamental design for a slide ruler, as shown and described.
